UNITED STATES PATENT OFFICE.

GEORGE E. MOLYNEUX, OF BAYONNE, AND GEORGE S. GATCHELL, OF ROSELLE PARK, NEW JERSEY, ASSIGNORS TO THE SINGER MANUFACTURING COMPANY, A CORPORATION OF NEW JERSEY.

SEAM-GUIDE FOR SEWING-MACHINES.

1,124,320.

Specification of Letters Patent. Patented Jan. 12, 1915.

Application filed July 20, 1912. Serial No. 710,616.

To all whom it may concern:

Be it known that we, GEORGE E. MOLYNEUX and GEORGE S. GATCHELL, citizens of the United States, residing, respectively, at 5 Bayonne, in the county of Hudson and State of New Jersey, and Roselle Park, in the county of Union and State of New Jersey, have invented certain new and useful Improvements in Seam-Guides for Sewing- 10 Machines, of which the following is a specification, reference being had therein to the accompanying drawings.

This invention is designed more particularly for use in connection with seam-covering machines comprising a plurality of spaced reciprocating needles arranged in a line transverse to the direction of feed and adapted, in conjunction with suitable loop-taking means, to produce a covering seam 20 embracing the cut edges of two sections of knit goods having their overlapped adjacent marginal portions secured together by overlock or other through-and-through stitches and opened out to receive the covering seam.

25 The invention has for its object to provide a seam covering machine of this character with means for so handling the work that it may be delivered therefrom with the upper face entirely or approximately flat 30 and free from the ridge which has usually been formed in the operation by reason of the distribution of the increased thickness of fabric at the seam partially upon the upper face and partially upon the lower face. 35 By maintaining the upper face of the fabric perfectly flat, or nearly so, throughout the seam-covering operation, the production of an objectionable ridge is avoided.

The invention has for its further object 40 to accurately guide the initial uniting seam midway between the needles of the covering-seam stitch-forming mechanism in order that the covering seam may be laid centrally of the uniting seam.

45 It has for a further object to adapt the device for effectively handling materials of different thicknesses.

In its preferred embodiment, the present improvement comprises a throat-plate 50 formed with spaced needle-apertures and intermediate rearwardly extending stitch-receiving tongue having in its upper or work-supporting face a longitudinal seam-

guiding groove extending from a point in advance of the needle-apertures to a position rearward of the same, such groove forming a continuation of a seam-guiding slot with seam-guiding walls afforded by spaced parallel guide-plates arranged below the face of the throat-plate and each formed with a shank secured for lateral adjustment upon the bottom of the throat-plate. Coöoperating with said throat-plate is a presser-foot which preferably has upon its forward portion a depending guide-fin entering said slot between the guide-plates with its operative or work-pressing portion flared upwardly and outwardly from said guide-fin. In order to properly deliver the seam to be covered to the stitch-forming mechanism, the lower edge of the guide-fin is preferably inclined rearwardly and upwardly to a point substantially between the needle-apertures, and the heel portion of the foot is formed with a clearance groove extending backwardly from the needle-apertures of said foot, so as to prevent the distortion of the covered seam as it is delivered from the stitch-forming mechanism under the action of the feeding mechanism.

In the accompanying drawings, Figure 1 is a front end view of the tubular work-support of the type represented in the United States Patent to G. E. Molyneux, No. 1,000,836, of August 15, 1911, with the end cap omitted, and Fig. 2 a side elevation of the same. Fig. 3 is a plan of the same with the needle-bar and presser-foot omitted. Fig. 4 is a bottom plan of the throat-plate detached. Fig. 5 is a longitudinal sectional elevation of the throat-plate and presser-foot. Fig. 6 is an end view, in section through the needle-apertures, of the throat-plate, presser-foot and needles, with a section of the material in place, and Fig. 7 a front end view of the same parts. Fig. 8 is a transverse section of the presser-foot through the axis of the transverse pivotal connection of the foot-plate with the shank, and Fig. 9 is a perspective view of one of the presser-foot guide-plates. Figs. 6 to 9, inclusive, are upon a larger scale than the preceding figures.

The tubular longitudinally extending horn or work-support 1 is provided with 105 the arched throat-plate 2 secured upon a de-

pressed seat in the upper side of the same by means of screws 3, and has a flat operative portion 4 extending beyond the extremity of the arm to sustain the work in 5 the stitching operation. As represented in the drawings, the throat-plate is provided with the usual feed-dog apertures 5 and with the spaced needle-apertures 6 from the outer sides of which extend backwardly 10 thread-clearance slits 7 into the central feed-dog aperture so as to form the stitch-receiving tongue 8 extending backwardly from the needle-apertures. Extending from the forward end of the throat-plate part- 15 way to the needle-apertures is the central seam-guiding slot 9 in register with which is the seam-guiding groove 10 formed in the upper face of the throat-plate and extending from a point in advance of the needle- 20 apertures intermediate the latter to a point near the rearward end of the tongue 8. As represented in Fig. 5, the groove 10 is at its forward end of nearly the depth of the throat-plate, and its bottom is extended up- 25 wardly to the rearward end beyond the needle-apertures where it merges in the flat upper face of the tongue.

Arranged within the seam-guiding slot 9 are the spaced and substantially parallel 30 guide-plates 11 whose adjacent faces afford the effective side walls of the slot. The upper edges of the plates 11 are shown flush with the flat top of the throat-plate, and adjacent their lower edges they are provided 35 each with a shank 12 formed with an elongated aperture 13 and secured upon suitable seats 14 formed in the bottom of the throat-plate (as represented in dotted lines in Fig. 7) by means of the fastening screw 15. By 40 loosening the screws 15, the guide-plates 11 may be shifted laterally toward and from each other to vary the width and adjust the lateral position of the guide-channel which initially receives the lap-seam to be covered.

45 To the outer end of the work-support is fitted the usual end cap 16 which is cut out in the upper side to receive the contracted forward portion of the throat-plate, and provided in the top of its forward extremity 50 in advance of the throat-plate with the seam-guiding notch 17 in register with the slot 9 of the throat-plate. The notch 17, slot 9 and groove 10 together form a continuous channel for directing the overlapping margins of 55 the fabric with their uniting seam from a point in advance of the needles to a point rearward of the needles.

As herein represented, the machine is provided with a reciprocating needle-bar 18 60 carrying the twin-needle clamp 19 in which are secured by means of the fastening screws 20 the shanks of two eye-pointed needles 21. Coöoperating with these needles is the thread- 65 carrying looper 22 whose shank 23 is mounted upon the rocking carrier 24 em-

braced by the end-cap 16 and deriving through any usual or suitable means endwise loop-seizing and shedding and sidewise needle-avoiding movements for laying a covering thread transversely of the direction 70 of feed between the thread-loops passed through the fabric by the needles 21.

The presser-bar 25 has secured to its reduced lower portion by means of the fastening screw 26 the presser-foot shank 27 having the forwardly and downwardly offset extension 28 channeled in its lower side to receive the tilting block 29 which is mounted therein upon the alined fulcrum-screws 30 carried thereby. The block 29 is embraced 80 between the transverse lugs 31 of the pressure plate 32 and is pivotally connected therewith by means of the longitudinal pin 33. The pins 30 and 33 constitute transverse fulcra forming with the tilting block 29 a 85 universal joint connection between the foot-plate and the shank 27, so as to enable the foot-plate to tilt both sidewise and endwise in accommodating itself to the work. The foot-plate is provided intermediate its ends 90 with needle-holes 34, and its upturned forward or toe portion is formed with the depending and forwardly extending guide-fin 35 entering the seam-guiding space between the plates 11 and having a lower edge inclined backwardly and upwardly to a point substantially intermediate the needle-apertures and slightly above the forward end of the seam-guiding groove 10 of the throat-plate. The forward portion of the foot-plate is flared upwardly and outwardly from the guide-fin, somewhat like the prow of a boat, so as to smooth out the material at the adjacent sides of the latter as it passes beneath the presser-foot. Extending rearwardly from a point in the bottom of the foot-plate substantially intermediate the needle-holes 34 is a longitudinal clearance groove 36 adapted to receive the portion of 100 the fabric thickened by the seam as it 110 emerges from the guiding groove 10.

The machine is provided with suitable feeding mechanism comprising the feed-dog 37 which is provided in the machine represented in the drawings with means for imparting thereto work-advancing movements longitudinally of the work-support 1 and the usual rising and falling movements.

In the use of the improvement as thus described, the material *m* is applied to the 120 work-support with the overlapping margins *m'*, secured together by the uniting seam *s*, passed through the guiding notch 17 of the end cover and between the spaced guide-plates 11 (Fig. 7) with the guide-fin 35 of 125 the presser-foot inserted in the crease above the uniting seam. The machine being set in motion, the work is advanced beneath the presser-foot and the body fabric adjacent the uniting seam is ironed out by the flared 130

toe portion of the presser-foot and distended to bring the marginal portions m' within the mouth of the throat-plate groove 10 through which it is guided not only to but beyond the needles so as to positively insure the presentation of the initial seam midway between the latter and thereby cause the covering seam to be laid with precision centrally of the initial uniting seam.

10 In the production of a chain-stitch covering-seam each stitch is commonly set at the completion of the thrust of the needles for the succeeding stitch, and after the action of the feed to advance the work. In order that the upper face of the work may remain flat and free from distortion by this stitch-setting action, the guiding groove 10 is preferably extended rearwardly in the tongue 8 a distance equivalent to the longest stitch-length, so that the margins m' of the fabric m will remain housed in such groove, as represented in Fig. 6, until the stitch is entirely completed, after which the emergence of the margins of the covered seam from the rearward extremity of the groove 10 upon the flat upper face of the throat-plate and the forcing of the upper face of the fabric into the clearance groove 36 of the presser-foot will not cause any appreciable change in the condition of the seam.

It will be observed that the two spaced rectilinearly reciprocating needles and the single looper coöperating therewith and adapted to lay a lower covering thread connecting the needle-thread loops thrust through the fabric by the needles constitutes a species of overseaming stitch-forming mechanism, and it is evident that the present improvement is equally adapted for employment with other types of overseaming mechanism designed to lay a covering thread or threads upon one or both faces of the fabric, as, for instance, in machines employing a laterally jogging needle, of a plurality of needles with one or more coöperating loop-takers and a vibratory thread-carrier for laying a thread between the needles transversely of the direction of seam. In any case the tongue 8 between the spaced needle apertures would be shaped in a manner well known to shed the stitches if formed over the same, as by employment of a laterally jogging needle.

Having thus set forth the nature of the invention, what we claim herein is:—

1. In a sewing machine, the combination with overseaming stitch-forming mechanism, and feeding mechanism, of a throat-plate provided with spaced needle-apertures and an intermediate tongue extending therefrom in the direction of feed and having in its upper face a seam-guiding groove.

2. In a sewing machine, the combination with overseaming stitch-forming mechanism, and feeding mechanism, of a throat-

plate provided with spaced needle-apertures and an intermediate tongue extending therefrom in the direction of feed and having in its upper face a seam-guiding groove terminating a distance greater than a stitch-length rearward of said needle-apertures. 70

3. In a sewing machine, the combination with overseaming stitch-forming mechanism, and feeding mechanism, of a throat-plate provided with spaced needle-apertures and with a seam-guiding slot in advance thereof and having also extending between and rearward of said needle-apertures a tongue containing in its upper face a seam-guiding groove forming a continuation of said slot and extending between and rearward of said needle-apertures. 75

4. In a sewing machine, the combination with overseaming stitch-forming mechanism, and feeding mechanism, of a throat-plate provided with spaced needle-apertures and with a seam-guiding slot in advance thereof and having also extending between and rearward of said needle-apertures a tongue containing in its upper face a seam-guiding groove forming a continuation of said slot and extending between and rearward of said needle-apertures, and a presser-foot formed in its toe-portion with a depending guide-fin entering said slot and extending to a point above said seam-guiding groove. 80

5. In a sewing machine, the combination with overseaming stitch-forming mechanism, and feeding mechanism, of a throat-plate provided with spaced needle-apertures and with a seam-guiding slot in advance thereof and having also extending between and rearward of said needle-apertures a tongue containing in its upper face a seam-guiding groove forming a continuation of said slot and extending between and rearward of said needle-apertures, and a presser-foot formed in its toe-portion with a depending guide-fin entering said slot and terminating above said seam-guiding groove and formed in its under side with a longitudinal clearance groove extending rearward of said groove of the throat-plate. 90

6. In a sewing machine, the combination with overseaming stitch-forming mechanism, and feeding mechanism, of a throat-plate provided with spaced needle-apertures and formed in advance thereof with a seam-guiding slot below its face whose 105 walls are relatively adjustable to vary the effective width of said slot. 115

7. In a sewing machine, the combination with overseaming stitch-forming mechanism, and feeding mechanism, of a throat-plate provided with spaced needle-apertures and formed in advance thereof with a seam-guiding slot, spaced parallel guide-plates disposed within and affording separate facings for said slot and formed with shanks 120 125 130

resting upon seats therefor formed in the bottom of the throat-plate, and means for adjustably securing said shanks in position.

8. In a sewing machine, the combination with overseaming stitch-forming mechanism, and feeding mechanism, of a throat-plate provided with a seam-guiding channel extending in advance of, between and rearward of said needle-apertures, and a presser-foot having a depending guide-fin entering said channel in advance of the needle-apertures and having the toe-portion of the foot flared upwardly and outwardly from said guide-fin.

15 9. A sewing machine throat-plate constructed with spaced needle-apertures transversely arranged and with an intermediate longitudinally extending tongue formed in its upper face with a longitudinal seam-

guiding groove extending between and rearward of said needle-apertures.

10. A sewing machine throat-plate constructed with spaced needle-apertures and with a seam-guiding slot in advance thereof with reciprocally adjustable side-walls and 25 having a tongue extending rearwardly from said needle-apertures and formed in its upper face with a seam-guiding groove continuous with said slot.

In testimony whereof, we have signed our 30 names to this specification, in the presence of two subscribing witnesses.

GEORGE E. MOLYNEUX.
GEORGE S. GATCHELL.
